UNITED STATES PATENT OFFICE

2,675,052

MACHINE FOR MANUFACTURING BINDING TAPES

John Stanley Robinson, Grand Rapids, Mich., assignor to Sackner Products, Inc., Grand Rapids, Mich.

Application December 3, 1951, Serial No. 259,597

13 Claims. (Cl. 154—1.6)

1

This invention relates to improvements in a machine for manufacturing binding tapes.

The embodiment of the invention illustrated is especially designed for the manufacture of the binding tapes such as substantially shown in the Wall and Reinhard Patent 2,570,614, issued October 9, 1951.

The main objects of this invention are:

First, to provide a machine for manufacturing binding tapes or ties comprising a metal ribbon or flat metal strand and a padding adhered thereto which is largely automatic and is of large capacity, requiring little attention on the part of the operator.

Second, to provide a machine of this character which produces a very uniform product.

Objects relating to details and economies of the invention will appear from the description to follow. The invention is pointed out in the claims.

A preferred embodiment of the invention is illustrated in the accompanying drawings, in which:

Fig. 1 is a side elevational view of a machine embodying the invention divided on the line A—A for convenience in illustration, certain parts being shown mainly in conventional form.

Fig. 2 is an enlarged fragmentary front elevational view of the rear portion of the machine as viewed on line A—A of Fig. 1 looking toward the rear, certain parts being omitted for convenience in illustration and for the sake of clearness.

Fig. 3 is a fragmentary view partially in longitudinal section.

Fig. 4 is a fragmentary view of the completed binding tape or tie produced by the machine.

Fig. 5 is an enlarged fragmentary view illustrating details of the portion of the machine designed for forming a composite portion of the tie, namely the padding element and the padding supporting element.

Fig. 6 is an enlarged fragmentary perspective view of the means for forming this composite portion or strip.

Fig. 7 is a perspective view illustrating the multiply padding material as supplied to the machine.

Fig. 8 is a fragmentary perspective view illustrating the padding element in its conformed shape and prior to the application of the supporting element thereto.

Fig. 9 is a fragmentary perspective view of the composite strip sectioned on a line corresponding to line 9—9 of Fig. 1.

Fig. 10 is a fragmentary perspective view of the

2

composite strip sectioned on a line corresponding to line 10—10 of Fig. 1 and showing the composite strip after it has been reversed or inverted.

As stated, the embodiment of the invention illustrated is especially designed for making the binding tape, the subject matter of the Wall and Reinhard Patent 2,570,615. The machine is in some respects an embodiment of and an improvement on the structure of the patent to Boersma and Robinson No. 2,560,923, issued July 17, 1951.

The binding tape which is designated generally by the numeral 1 in Fig. 4 comprises a metal ribbon or strand element 2, a padding element 3, and a padding backing strip 4 of paper interposed between the metal strand and the padding. The backing strip 4 is of a width substantially exceeding the width of the metal strand and is adhered to the inner side of the metal strand.

The padding, which is desirably formed of multiply tissue folded upon itself, is adhered to the inner side of the supporting strip 4.

The machine of this application is designed to form the padding element 3 (see Fig. 8) from multiply strips of tissue 7 (see Fig. 7) and to apply the supporting strip or element 4 to the conformed padding strip to produce the composite strip designated generally by the numeral 8 in Fig. 9. The composite strip 8 is first formed as a continuous strip and is then cut into sections and adhesively secured to the metal ribbon or strand element 2 with the adjacent ends of the sections in spaced relation to each other and spaced relative to the scores 5 in the metal element indicated in Fig. 4 by dotted lines. These scores facilitate the breaking or severing of the continuous strip into tie length and provide tie sections 6 at each end of the padding. One use of this material is illustrated in the Wall and Reinhard Patent 2,570,614.

For convenience and economy in manufacture the operative parts are supported on frames designated generally by the numerals 10, 11, 12, 13 and 14, these being arranged in alignment. The frame 10 is designed to support a plurality of reels or spools 15 for strips of padding material 7 and a spool or reel 16 for the strip of padding backing material 4. As illustrated, two strips of the padding material are employed in forming the padding element.

The strips 7 are guided by the guide rollers 17, conventionally shown in Fig. 1, to the forming member 18 which is provided with converging edge folders 19 which fold the edges of the padding material upwardly and inwardly into edge

abutting relation as shown at 20 in Fig. 8. The padding supporting strip 4 is guided by the roller 21 to the guide throat 22 disposed in advance of the glue or adhesive applying roller 24, this roller dipping into the adhesive receptacle 25. From the glue roller the strip 4 is guided by the guide throat 26 into superimposed relation to the padding strip and its adhesive surface is superimposed upon the inturned edges of the padding strip as is shown in Fig. 9.

The padding material and the backing material therefor is drawn from the spools or reels and through the forming dies and across the adhesive applying roller by means of the co-acting pressure and feed belts designated generally by the numerals 27 and 28, these being supported so that their opposed reaches travel rearwardly and apply driving and sealing pressure to the composite strip. The belts are trained over the rollers 29 and 29' which are geared to each other and driven by the chain 30 from the transmission assembly designated generally by the numeral 31. This transmission assembly is driven from a motor 32 through the chain 33 and suitable sprockets. As the details of this mechanism are not part of this invention they are not illustrated herein. This first pair of feed and driving belts are the same in structure as the second pair of feed and driving belts which are illustrated in more detail in Fig. 3 and will be described later.

The first pair of feed and pressure belts are of such length as to allow the adhesive to set before the composite strip is discharged from the belts. As it is discharged from these belts it is formed into a take-up loop 34 and the loop is given a half twist, as indicated at 35, so that as discharged over the guide roller 36 the padding supporting element 4 is on the under side of the composite strip as shown in Fig. 10, it being shown in Fig. 9 in the position in which it is discharged from the first pair of feed and pressure belts. The speed of the machine is controlled by the hand wheel 37, the sprocket chain 37' and suitable sprockets to the driven shaft of the variable speed transmission assembly (see Fig. 1). The loop is formed by the difference in speed of the pad forming machine, and the metallic strip applying machine.

From the roller 36 the composite strip is passed through the guide 38 to the feed rollers 39 and 40, the feed roller 39 being a driven roller and the feed roller 40 a pressure roller. At the rear of the feed rollers is a cutter comprising a cutter bar 41 and the reciprocating cutter blade or knife 42. At the rear of the knife is a guide 43 having an opening 44 in its under wall through which the glue or adhesive applying roller 45 projects to coat with the padding backing strip 4 of the composite strip 8 which is then in position with its padding supporting strip 4 downward or on the under side. The guide 43 directs the composite strip with the adhesive thereon to the second pair of the feed and pressure belts 46, the adjacent cooperating reaches thereof traveling rearwardly. A series of belt supporting rollers 47 are provided for the opposed reaches of the belts so that the belts are firmly pressed against the work passing therebetween. The ribbon steel element 2 is directed by the guide 48 against the lower belt as it passes around the front pulley 49, as shown in Fig. 3, so that the metal strand is directed upon and pressed against the adhesive bearing surface of the strip 4. The rear ends of the

belts 46 are supported and driven by the pulleys 50 which are geared together, the gears not being shown.

The lower pulley 50 is driven by the sprocket chain 51 coacting with a suitable sprocket on the jackshaft 52. The metal element or strand 2 is drawn from a spool or reel 2' on the frame or pedestal 13. The upper feed belts of both units are adjustably supported by means of the screws 53 for regulating the pressure thereof and adjusting the same to the thickness of the material used.

The scores, indicated at 5 in Fig. 4, are formed by means of the serrated or toothed scoring blade 54 mounted on the roller 55 in opposed relation to the supporting roller 56. The roller 56 is provided with a bearing member 57 adjustably supported in the frame 58 by means of the screws 59, only one of which is illustrated. The roller or scoring blade 54 is driven in timed relation to the intermittent feed roller 39 so that the composite strip sections delivered from the intermittent feed roller and the cutter to the feed and pressure belts are delivered with their ends in spaced relation to the scores of the metal strand element providing the tie sections 6.

To drive these several parts in timed relation the jackshaft 52 is driven from the driven shaft of the variable speed transmission by the driving chain 60 on the sprocket 61 on the jack-shaft. The driving roller 39 and the glue roller 45 are driven from the jackshaft through the chain 62 and a sprocket indicated at 63 on the jackshaft. The shaft 64 of the feed roller 39 is intermittently driven through the clutch designated generally by the numeral 65. The details of this clutch are not illustrated but it is actuated through the rockshaft 66 having an arm 67 coacting with the clutch actuating member 68. The rockshaft is provided with an arm 69 with which the cam 70 on the shaft 71 contacts. The shaft 71 is driven through the clutch 72 and the sprocket chain 73 to the jackshafts 52. The clutch actuating arm 74 is actuated through the tappet arm 75 which is positioned to be engaged by tappets 76 on the sprocket chain 71. This sprocket chain is designed to be lengthened and shortened by taking out one or more links, it being adjustably supported by the adjustable sprockets 78 (see Fig. 1). The arm 74 is connected by the link 79 to the clutch actuating arm 80 for the scoring cutter 55. The details of these clutches are not illustrated as they form no part of the present invention.

The shaft 71 is provided with a cam 81 which coacts with the roller 82 on the lower end of the connecting rod 83 which is supported by the rocker arm 84 at its lower end and is connected to the cutter actuating lever 85 pivoted at 86 and pivotally connected at 87 to the cutter blade 42. A spring 88 is provided for retracting the cutter blade.

The feed roller 39 is provided with an overrunning clutch, designated generally by the numeral 89, and with a brake 90. The brake is controlled by the arm 91 which is actuated by the link 92 carried by the lever 85. A spring 93 is interposed between the thrust member 94 on the link and the arm 91.

To prevent overrunning of the shaft 71 it is provided with a friction drag designated generally by the numeral 95. The metal strip element 2 is passed over the support 96 with which the microswitches 97 are associated so that in the event of the breaking or running out of the

strand 2, the switches are actuated to stop the machine. The wiring for the switches to the motor 32 is not illustrated.

The pressure roller 40 is yieldingly urged toward the feed roller 39 by means of the springs 98. The glue pan 99 with which the glue roller 45 is associated is provided with a heating element 100 connected to a suitable current source through the cable indicated at 101 (see Fig. 2). The complete binding tape is passed through the winding guide 102 to the reel 103 which is driven through the chain 104 and suitable sprockets. The winding guide 102 is carried by an arm 106 which is pivoted at 107 and operatively associated with a cam 108 which is connected by the sprocket chain 109 and suitable gears to the winding reel shaft 110.

I have not illustrated and described various details as they form no part of my present invention and some of them are detailed in the aforementioned Boersma and Robinson patent, this invention being, as stated, an improvement upon and an adaptation of certain features disclosed in the aforesaid patent and in the co-pending application for patent of Boersma and Robinson, Serial Number 89,058, filed April 22, 1949.

I have illustrated and described the invention in a highly practical embodiment thereof. I have not attempted to illustrate or describe certain embodiments and adaptations which I contemplate as it is believed that this disclosure will enable those skilled in the art to embody or adapt the invention as may be desired.

Having thus described my invention, what I claim as new and desire to secure by Letters Patent is:

1. A machine for manufacturing binding tape comprising a flexible metal strand element, a padding supporting strip element of paper adhesively secured to the metal strand, and a padding element of multiply tissue adhesively secured to the inner side of the paper strip element, said machine comprising a first pair of continuously driven feed and pressure belts having coacting rearwardly traveling reaches, means for guiding a plurality of strips of tissue padding material into superimposed relation and folding the edges thereof inwardly, means for applying adhesive to the traveling padding supporting strip element and guiding the same with the adhesive bearing surface thereof upon the infolded edge side of said padding element and guiding the composite strip to said belts, a guide roller disposed at the rear of and in spaced relation to said belts permitting the composite strip being disposed in an inverting twist loop to position the padding supporting strip element on the under side of the composite strip, a continuously driven second pair of feed and pressure belts having coacting rearwardly traveling reaches, means for intermittently feeding the inverted composite strip disposed rearwardly of the first pair of belts and in advance of and in spaced relation to said second pair of belts, a cutter disposed at the rear of said intermittent feed means and actuated in timed relation thereto for severing the composite strip into sections, means for applying adhesive to the paper element of said composite strip disposed between said cutter and said second pair of belts, means for supporting and guiding the metal strand element to said second pair of belts and into contact with the adhesive bearing surface of the paper strip element of said composite strip, and

means for transversely scoring the metal strand element at spaced points facilitating the fracturing thereof at such points disposed in advance of the second pair of belts, said cutter and said means for intermittently feeding said composite strip being actuated in timed relation to said metal strand element scoring means so that the ends of composite strip sections are spaced relative to the scores of the metal strand element.

10 2. A machine for manufacturing binding tape comprising a flexible metal strand element, a padding supporting strip element of paper adhesively secured to the metal strand, and a padding element adhesively secured to the inner side of the paper strip element, said machine comprising a first pair of continuously driven feed and pressure members, means for guiding the padding element, means for applying adhesive to the traveling padding supporting strip element and guiding the same with the adhesive bearing surface thereof upon said padding element and guiding the composite strip to said feed and pressure members, a composite strip guiding means disposed at the rear of and in spaced relation to said feed and pressure members permitting the composite strip being disposed in an inverting twist loop to position the padding supporting strip element on the under side of the composite strip, a continuously driven second pair of feed and pressure members, means for intermittently feeding the inverted composite strip disposed rearwardly of the first pair of belts and in advance of and in spaced relation to said second pair of feed and pressure members, a cutter disposed at the rear of said intermittent feed means and actuated in timed relation thereto for severing the composite strip into sections, means for applying adhesive to the paper element of said composite strip disposed between said cutter and said second pair of feed and pressure members, means for supporting and guiding the metal strand element to said second pair of feed and pressure members and into contact with the adhesive bearing surface of the paper strip element of said composite strip, and means for transversely scoring the metal strand element at spaced points facilitating the fracturing thereof at such points disposed in advance of the second pair of belts, said cutter and said means for intermittently feeding said composite strip being actuated in timed relation to said metal strand element scoring means so that the ends of composite strip sections are spaced relative to the scores of the metal strand element.

55 3. A machine for manufacturing binding tape comprising a flexible metal strand element, a padding supporting strip element of paper adhesively secured to the metal strand, and a padding element of multiply tissue adhesively secured to the inner side of the paper strip element, said machine comprising a first pair of feed and pressure members, means for guiding a plurality of strips of tissue padding material into superimposed relation and folding the edges thereof inwardly, means for applying adhesive to the traveling padding supporting strip element and guiding the same with the adhesive bearing surface thereof upon the infolded edge side of said padding element and guiding the composite strip to said feed and pressure members, a composite strip guiding means disposed at the rear of and in spaced relation to said feed and pressure members permitting the composite strip being disposed in an inverting twist loop to position the padding supporting strip element on the under

side of the composite strip, a second pair of feed and pressure members, means for intermittently feeding the inverted composite strip to said second pair of feed and pressure members, a cutter disposed at the rear of said intermittent feed means and actuated in timed relation thereto for severing the composite strip into sections, means for applying adhesive to the paper element of said composite strip disposed between said cutter and said second pair of feed and pressure members, and means for supporting and guiding the metal strand element to said second pair of feed and pressure members and into contact with the adhesive bearing surface of the paper strip element of said composite strip, said cutter and intermittent feed means being timed to deliver composite strip sections in spaced relation.

4. A machine for manufacturing binding tape comprising a flexible metal strand element, a padding supporting strip element of paper adhesively secured to the metal strand, and a padding element of multiply tissue adhesively secured to the paper strip element, said machine comprising a first pair of continuously driven feed and pressure belts having coacting rearwardly traveling reaches, means for guiding a plurality of strips of tissue padding material into superimposed relation and folding the edges thereof inwardly, means for applying adhesive to the traveling padding supporting element and guiding the same with the adhesive bearing surface thereof upon the infolded edge side of said padding element and guiding the composite strip to said belts, a guide roller disposed at the rear of and in spaced relation to said belts permitting the composite strip being disposed in an inverting twist loop, a continuously driven second pair of feed and pressure belts having coacting rearwardly traveling reaches, means for intermittently feeding the inverted composite strip disposed at the rear of the guide roller and in advance of and in spaced relation to said second pair of belts, a cutter disposed at the rear of said intermittent feed means and actuated in timed relation thereto for severing the composite strip into sections, means for applying adhesive to the paper element of said composite strip disposed between said cutter and said second pair of belts, means for supporting and guiding the metal strand element to said second pair of belts and into contact with the adhesive bearing surface of the paper strip element of said composite strip, and means for transversely scoring the metal strand element at spaced points facilitating the fracturing thereof at such points disposed in advance of the second pair of belts, said cutter and said intermittent feed means being actuated in timed relation to the said metal strand element scoring means so that the ends of the composite strip sections are spaced relative to the scores of the metal strand element.

5. A machine for manufacturing binding tape comprising a flexible metal strand element, a padding supporting strip element of paper adhesively secured to the metal strand, and a padding element adhesively secured to the paper strip element, said machine comprising a first pair of continuously driven feed and pressure belts having coacting rearwardly traveling reaches, means for guiding a padding element, means for applying adhesive to the traveling padding supporting element and guiding the same with the adhesive bearing surface thereof upon the said padding element and guiding the composite strip to said belts, a guide roller disposed at the rear of and

in spaced relation to said belts permitting the composite strip being disposed in an inverting twist loop, a continuously driven second pair of feed and pressure belts having coacting rearwardly traveling reaches, means for intermittently feeding the inverted composite strip disposed at the rear of the guide roller and in advance of and in spaced relation to said second pair of belts, a cutter disposed at the rear of said intermittent feed means and actuated in timed relation thereto for severing the composite strip into sections, means for applying adhesive to the paper element of said composite strip disposed between said cutter and said second pair of belts, and means for supporting and guiding the metal strand element to said second pair of belts and into contact with the adhesive bearing surface of the paper strip element of said composite strip, and means for transversely scoring the metal strand element at spaced points facilitating the fracturing thereof at such points disposed in advance of the second pair of belts, said cutter and said intermittent feed means being actuated in timed relation to the said metal strand element scoring means so that the ends of the composite strip sections are spaced relative to the scores of the metal strand element.

6. A machine for manufacturing binding tape comprising a flexible metal strand element, a padding supporting strip element of paper adhesively secured to the metal strand, and a padding element of multiply tissue adhesively secured to the paper strip element, said machine comprising a first pair of continuously driven feed and pressure belts having coacting rearwardly traveling reaches, means for guiding a plurality of strips of tissue padding material into superimposed relation and folding the edges thereof inwardly, means for applying adhesive to the traveling padding supporting element and guiding the same with the adhesive bearing surface thereof upon the infolded edge side of said padding element and guiding the composite strip to said belts, a guide roller disposed at the rear of and in spaced relation to said belts permitting the composite strip being disposed in an inverting twist loop, a continuously driven second pair of feed and pressure belts having coacting rearwardly traveling reaches, means for intermittently feeding the inverted composite strip disposed at the rear of the guide roller and in advance of and in spaced relation to said second pair of belts, a cutter disposed at the rear of said intermittent feed means and actuated in timed relation thereto for severing the composite strip into sections, means for applying adhesive to the paper element of said composite strip disposed between said cutter and second pair of belts, and means for supporting and guiding the metal strand element to said second pair of belts and into contact with the adhesive bearing surface of the paper strip element of said composite strip.

7. A machine for manufacturing binding tape comprising a flexible metal strand element, a padding supporting strip element of paper adhesively secured to the metal strand, and a padding element adhesively secured to the paper strip element, said machine comprising a first pair of continuously driven feed and pressure belts having coacting rearwardly traveling reaches, means for guiding a padding element, means for applying adhesive to the traveling padding supporting element and guiding the adhesive bearing surface thereof upon the said padding element and guiding the composite strip to

said belts, a guide roller disposed at the rear of and in spaced relation to said belts permitting the composite strip being disposed in an inverting twist loop, a continuously driven second pair of feed and pressure belts having coacting rearwardly traveling reaches, means for intermittently feeding the inverted composite strip disposed at the rear of the guide roller and in advance of and in spaced relation to said second pair of belts, a cutter disposed at the rear of said intermittent feed means and actuated in timed relation thereto for severing the composite strip into sections, means for applying adhesive to the paper element of said composite strip disposed between said cutter and said second pair of belts, and means for supporting and guiding the metal strand element to said second pair of belts and into contact with the adhesive bearing surface of the paper strip element of said composite strip.

8. In a machine for manufacturing a binding tape comprising a metal strand element and a padding strip element adhered thereto from a continuous strip of padding material and a continuous strip of metal, the combination of coacting feeding and pressure members comprising belts having coacting rearwardly traveling reaches, means for intermittently feeding a padding strip element comprising an intermittently driven feed roller provided with an overrunning driving clutch therefor and a coacting pressure roller, a cutter for severing the padding strip element disposed at the rear of said feed roller and including a shear bar and a reciprocatingly mounted cutter blade, a return spring for said blade, an actuating lever for said blade, an actuating rod for said lever, a cam for actuating said rod, driving means, means connecting said driving means to said coacting feeding and pressure members, overrunning clutch and cam for driving the same, a brake for said feed roller, operating connections for said brake to said blade actuating lever whereby the feed roller is stopped when the knife is actuated, means for applying the adhesive to the padding strip disposed between said feed roller and said feed and pressure belts, means for supporting and guiding a metal strand to said feed and pressure belts and against the adhesive bearing side of said padding strip, and means for transversely scoring the metal strip element at spaced points facilitating the fracturing thereof, said cutter and intermittent feed roller being actuated in timed relation to said metal strip scoring means so that the ends of the composite strip sections are spaced relative to the scores of said metal strand element.

9. In a machine for manufacturing a binding tape comprising a metal strand element and a padding strip element adhered thereto from a continuous strip of padding material and a continuous strip of metal, the combination of coacting feeding and pressure members comprising belts having coacting rearwardly traveling reaches, means for intermittently feeding a padding strip element comprising an intermittently driven feed roller and a coacting pressure roller disposed forwardly of said feed and pressure belts, a cutter for severing said padding strip element disposed at the rear of said feed roller and forwardly of said feed and pressure belts and including a shear bar and a reciprocatingly mounted cutter blade, a return spring for said blade, an actuating lever for said blade, an actuating rod for said lever, a cam for actuating said rod, driving means, means connecting said driv-

ing means to said feeding and pressure members, intermittently driven feed roller and cam for driving the same, means for applying the adhesive to the padding strip disposed between said feed roller and said feed and pressure belts, means for supporting and guiding a metal strand to said feed and pressure belts and against the adhesive bearing side of said padding strip, and means for transversely scoring the metal strip element at spaced points facilitating the fracturing thereof, said cutter and intermittent feed roller being actuated in timed relation to said metal strip scoring means so that the ends of the composite strip sections are spaced relative to the scores of said metal strand element.

10. In a machine for manufacturing a binding tape comprising a metal strand element and a padding strip element adhered thereto from a continuous strip of padding material and a continuous strip of metal, the combination of coacting continuously driven feeding and pressure members, means for intermittently feeding a padding strip element comprising an intermittently driven feed roller provided with an overrunning driving clutch therefor and a coacting pressure roller, a cutter for severing said padding strip element disposed at the rear of said feed roller and forwardly of said feeding and pressure members and including a shear bar and a coacting cutter blade, an actuating lever for said blade, an actuating rod for said lever, a driving means, means connecting said driving means to said feeding and pressure members, intermittently driven feed roller and rod for driving the same, a brake for said feed roller, operating connections for said brake to said blade actuating lever whereby the feed roller is stopped when the knife is actuated, means for applying the adhesive to the padding strip disposed between said feed roller and said feeding and pressure members, and means for supporting and guiding a metal strand to said feeding and pressure belts and against the adhesive bearing side of said padding strip, said cutter and intermittent feed roller being actuated so that the composite strip sections are spaced along said metal strand element.

11. In a machine for manufacturing a binding tape comprising a metal strand element and a padding strip element adhered thereto from a continuous strip of padding material and a continuous strip of metal, the combination of coacting continuously driven feeding and pressure members, means for intermittently feeding a padding strip element comprising an intermittently driven feed roller provided with an overrunning driving clutch therefor and a coacting pressure roller, a brake for said driven feed roller, a cutter disposed at the rear of said feed roller and including a shear bar and a coacting cutter blade, a driving means, means connecting said driving means to said feeding and pressure members, said overrunning clutch and said cutter blade to actuate the same, the connection from said driving means to said cutter blade constituting positive means to actuate the cutter blade to sever the padding strip element, means for applying the adhesive to the padding strip disposed between said feed roller and said feed and pressure members, and means for supporting and guiding a metal strand to said feed and pressure belts and against the adhesive bearing side of said padding strip, said cutter and intermittent feed roller being actuated so that the composite

strip sections are spaced along said metal strand element.

12. A machine for the manufacture of binding tape comprising a flexible metal strand element, a padding supporting strip element and a padding strip element, all adhesively secured together, said machine comprising pressure and intermittent feeding means, means disposed in advance of said pressure and intermittent feeding means for guiding said padding supporting strip element and said padding strip element in superimposed relation to each other and for guiding said elements to said pressure and intermittent feeding means, means for applying adhesive to the inner side of one of said elements prior to delivery thereof to said pressure and intermittent feeding means for adhesively connecting the same to each other to form a composite strand, cutting means disposed at the rear of said pressure and intermittent feeding means for severing said composite strand into sections, an opposed pair of feed and pressure members disposed at the rear of said cutting means for receiving said severed sections from the cutting means, means for guiding the metal strand element to said opposed pair of feed and pressure members and into lapping relation to said severed sections of the composite strand, means for applying adhesive between the lapping sides of said metal strand element and said severed sections prior to the delivery thereof to said pair of opposed feed and pressure members to adhesively secure said severed sections to said metal strand element, and driving means connected to said pressure and intermittent feeding means, said cutting means and said opposed pair of feed and pressure members for actuating the same in timed

relation to each other so that said severed sections are disposed in longitudinally spaced relation on said metal strand element.

13. In a machine for manufacturing binding tape comprising a metal strand element and a padding strip element, the elements being adhesively connected, the combination of means for intermittently feeding the padding strip element, means disposed at the rear of said intermittent feeding means for severing the padding strip element into sections, feeding and pressure means disposed at the rear of said severing means for receiving the severed sections from said severing means, means for guiding the metal strand element to said feeding and pressure means and in lapping relation to said severed sections, means for applying adhesive between said metal strand element and said severed sections prior to delivery to said feeding and pressure means for adhering the same to each other, driving means, and means connecting said driving means to said intermittent feeding means, severing means and said feeding and pressure means for actuating the same in timed relation to each other so that the severed sections are disposed in longitudinally spaced relation on said metal strand element, the connecting means from the driving means to the severing means constituting positive means to actuate the severing means from the driving means when severing the padding strip element into sections.
